ATTORNEYS.

UNITED STATES PATENT OFFICE

ALBERT CHARLES GIENGER, OF CASCADE SUMMIT, OREGON

AIRPLANE

Application filed September 14, 1929. Serial No. 392,680.

My invention relates to improvements in airplanes, and it consists in the combinations, constructions and arrangements hereinafter described and claimed.

5 An object of my invention is to provide an airplane that employs one or more cylindrical members for aiding in lifting and guiding the airplane. I mount the power plant and the propellers within the cylindrical members.

10 A further object of my invention is to provide means for aiding in guiding the airplane. This means consists of a flat member centrally disposed with respect to the cylinder and extending rearwardly to the airplane elevator. The air stream flowing through the cylinder is divided by the flat member, and these two streams striking the member tend to hold the airplane on an even keel.

In the drawings I have shown two cylinders, although the number may be changed at will.

Other objects and advantages will appear as the specification proceeds, and the novel features will be particularly pointed out in the claims hereto annexed.

My invention is illustrated in the accompanying drawing, in which:

Figure 1 is a top plan view of the device, Figure 2 is a front elevation, and

30 Figure 3 is a section through one of the cylinders.

In carrying out my invention, I provide a fuselage 1 of the shape shown in Figure 1, and on either side I mount a cylinder 2. In Figure 1 I have shown these cylinders as having a length corresponding to the distance between the leading edge 3 and the trailing edge 4 of a lifting wing 5. The length of the cylinder may be changed to suit the design of the craft.

Referring to Figure 3, it will be noted that I mount an engine 6 within the cylinder 2. This engine is carried by braces 7 that extend to the wall of the cylinder. A shaft 8 projects forwardly and rearwardly of the en-

gine and carries a front propeller 9 and a rear propeller 10, both of which are mounted within the cylinder. The front propeller is disposed at the entrance of the cylinder, while the rear propeller may be disposed anywhere 50 in back of the engine. Both propellers are driven by the same engine.

It will be noted from Figure 1 that flat planes 11 extend rearwardly from the backs of the cylinder 2. Figure 3 shows how each plane 11 is centered with respect to the cylinder. The planes terminate at the rear elevators 12. Figure 3 shows a bar-like tail skid 13 as extending from the cylinder 2 to the rear of the plane 11.

From the foregoing description of the various parts of the device, the operation thereof may be readily understood.

The airplane is flown in the usual manner, and it is more readily kept on an even keel 65 because the planes 11 are centrally disposed with respect to the cylinders 2 and extend rearwardly therefrom. The propellers 9 and 10 drive the air through the cylinders, and this air flows above and below the planes 11. The flowing of this air above and below the planes has a greater stabilizing effect than if the planes were not provided. The planes also have an added lifting effect.

Although I have shown and described one embodiment of my invention, it is to be understood that the same is susceptible of various changes, and I reserve the right to employ such changes as may come within the scope 80 of the invention as claimed.

I claim:

1. An airplane construction comprising a fuselage including a rudder and an elevator arranged at the trailing end thereof, a tubular member disposed on each side of the fuselage, an engine mounted in each tubular member, propellers disposed within said tubular members and actuated by their respective engines, and flat planes extending rearwardly 85 90

from the ends of the tubular members and being disposed midway between the tops and bottoms thereof and terminating in the elevator on the fuselage.

- 5 2. An airplane construction comprising a fuselage having an elevator and a rudder associated therewith, a tubular member disposed on each side of the fuselage, the axes of the tubular members and the fuselage being
10 disposed in the same horizontal plane, means for forcing air through the tubular members, and flat planes extending rearwardly from the ends of the tubular members positioned midway between the tops and bottoms of the
15 tubular members.

ALBERT CHARLES GIENGER.
